United States Patent Office.

PHILANDER BYRNS, OF MINDORO, WISCONSIN.

Letters Patent No. 92,581, dated July 13, 1869.

IMPROVEMENT IN HAND GARDEN-CULTIVATOR.

The Schedule referred to in these Letters Patent and making part of the same.

To all whom it may concern:

Be it known that I, PHILANDER BYRNS, of Mindoro, in the county of La Crosse, and State of Wisconsin, have invented certain new and useful Improvements in Hand Garden-Cultivator; and I do hereby declare that the following is a full, clear, and exact description thereof, reference being had to the accompanying drawings, and to the letters of reference marked thereon, which form a part of this specification, and in which—

Figure 1 represents a perspective view of my wheelbarrow and cultivator; and

Figure 2, a perspective view of my wheelbarrow, cultivator, and waterer combined.

Similar letters indicate like parts in both figures.

The nature of my invention consists in the employment of a wheelbarrow, provided at its front end with cultivators, and above with a water-tank, substantially in the manner and for the purpose herein-after set forth.

To enable others skilled in the art to which my invention appertains, to make and use the same, I will now describe its construction and operation.

In the accompanying drawings—

A represents an ordinary wheelbarrow, and

B, a frame pivoted to the sides of the front end of the barrow A, as seen in fig. 1.

a is a bar attached to the front end of frame B by the screws b b.

c c c represent the cultivators attached between the front bar of the frame B and the bar a, and are adjusted to plow deep or shallow by the screws b b.

D represents the water-tank, provided at its upper side with the sliding door d, and inside with a slide operated by the lever d'.

The slide works over holes in the front side of the tank. To these holes are attached the pipes B' B', which connect with the box or sprinkler E, which is provided on its front side with a perforated plate, e.

Having thus described my invention,

What I claim as new, and desire to secure by Letters Patent, is—

The combination of the barrow A, pivoted frame B, cultivators c c c, water-tank D, provided with sliding door d, lever d', pipes B' B', and sprinkler E, all combined, arranged, and operating substantially in the manner and for the purpose described.

In testimony that I claim the foregoing as my own, I affix my signature, in presence of two witnesses.

PHILANDER BYRNS.
